OF SYRACUSE, NEW YORK, A CORPORATION OF NEW YORK.

ELECTRICAL COUPLING.

1,107,401.

Specification of Letters Patent. Patented Aug. 18, 1914.

Application filed July 25, 1910. Serial No. 573,692.

To all whom it may concern:

Be it known that I, CARL H. BISSELL, of Syracuse, in the county of Onondaga and State of New York, have invented a certain 5 new and useful Electrical Coupling, of which the following is a specification.

My invention relates to electrical couplings, and the object thereof is to provide a simple, durable and efficient device for 10 connecting two conductors to each other, or one conductor to a suitable support; and it consists in the combinations and constructions hereinafter set forth and claimed.

In describing this invention, reference is 15 had to the accompanying drawings, in which like characters designate corresponding parts in all the views.

Figure 1 is an elevation, partly broken away and in section, of one form of this 20 coupling and two conductors connected thereby. Fig. 2 is an end elevation, partly in section, of parts seen in Fig. 1. Fig. 3 is an end elevation, partly in section, of the detached coupling, one of the sections of the 25 band or strap member being shown as disconnected from the nut and swung upwardly. Fig. 4 is a side elevation of the main member of the coupling.

This coupling comprises generally a section 30al band or strap member, a main member having means coacting with the band or strap member for clamping a conductor passing through the bore of the band or strap member, said main member also having means for engaging a second conductor or support, and a nut for coacting with the two members.

In the illustrated embodiment of my invention, the band or strap member comprises 40 two segmental sections 1 and 2 pivotally connected at corresponding ends to each other, as at 3, and provided at their free ends with opposing, laterally extending, externally threaded projections 4 and 5.

The main member of the coupling is provided at one end with a head 6 having an 45 arcuate surface 7 for engaging a conductor 8 extending through the bore of the band or strap member, is provided at its opposite end 9 with a threaded portion 10 and with means for engaging a second conductor or support 11, and is provided intermediate of the head 6 and the end 9 with a shank 12.

In this exemplification of my invention, the 50 means associated with the end 9 of the main

member for engaging a second conductor or support 11 comprises a contractible sleeve 13 having a tapering periphery complementary to a socket or bore 14 in the end 9, and a nut 15 turning on the lower part of the threaded portion 10 and provided with a shoulder 16 for engaging the end of the sleeve 13 and forcing the latter into the socket 14 and thereby contracting the sleeve 13 about the end of the conductor or support 11.

The head 6 of the main member of the coupling is designed to operate between the sections 1 and 2 of the band or strap member, or within the bore of said member, and 60 is disposed with its greater length parallel to the axis of such bore, and the surface 7 thereof is designed to coöperate with the inner faces of the sections 1 and 2 so that the conductor 8 would be firmly engaged 65 substantially at all points about the part of its periphery located between said sections 1 and 2.

The nut 17 associated with the band and main members of the coupling serves to 70 force these parts into clamping position, and also to secure one of the sections of the band member against separation from the main member of the coupling while permitting the movement of the other section of the 75 band member about the pivot 3 to admit the conductor 8 within the bore of the band member; and this nut when properly adjusted admits of the band member being entirely separated from the main member. 80

In the accompanying drawing this nut 17 engages the threaded portion 10 of the main member and the threads of the projections 4 and 5, and when the nut 17 is screwed above the threaded portion 10 and engaged 85 with the threads of the projections 4 and 5 as illustrated in Figs. 1 and 2 the upper edge of the nut coacts with shoulders 18 which are provided on the head 6 and project laterally beyond opposite sides of the 90 shank 12 and between and beyond the contiguous faces of the threaded projections 4 and 5. Consequently, as the nut 17 is screwed toward the head 6, the surface 7 of the main member and the inner faces of the 95 sections 1 and 2 of the band member are forced into firm contact with the conductor 8 extending through the band or sleeve member.

The inner faces of the projections 4 and 5 100

2

are flat, and opposite sides of the shank 12 are formed with longitudinal recesses 19 having flat faces which are disposed in substantially the same planes as the sides of the shoulders 18 and engage the flat faces of the projections 4 and 5, one recess 19 extending lengthwise of the shank 12 to the threaded portion 10 of the main member and receiving the longer projection 5, and the other recess 19 being of less length and receiving the shorter projection 4. The sides of the intermediate portion of the main member beneath the shoulders 18 are of less diameter than the threaded ends of the projections 15 4 and 5 so that the nut 17 passes freely over such sides. Owing to the broad flat faces 19 of the shank 12 wide bearings are provided for the projections 4, 5 and twisting or movement of the projections 4, 5 and parts carried thereby relatively to each other during the turning of the nut 17 onto the projections 4, 5, is prevented, and further owing to such flat faces, the shank 12 and sections 4, 5 can be more economically manufactured 20 than if the faces 19 were of other shape and the sections 4, 5 provided with depressions for receiving projecting portions of the shank. As the nut 17 is turned in one direction, it engages the shoulders 18, and 25 being then engaged with the projections 4 and 5, effects relative movement of the band and main members of the coupling for clamping the conductor 8 between the surface 7 and the opposing faces of the band member. Upon turning the nut 17 in the reverse direction, the same engages the threaded portion 10 of the main member and when said nut is sufficiently turned in such reverse direction, it is disengaged from 30 the projection 4, thus permitting the section 1 of the band member to be swung upwardly to remove or admit the conductor 8, and at the same time the projection 5 is engaged by the nut 17, thus uniting the band and 35 main members of the coupling. By continuing this reverse movement of the nut 17 it will be disengaged from the projection 5, thus permitting the removal of the band member from the main member of the 40 coupling.

What I claim, is:—

1. In an electrical coupling, a band member comprising two sections pivotally connected to each other at corresponding ends 55 and provided at their opposite ends with externally threaded projections having opposing flat faces, a main member having at one end an engaging surface for co-operating with the inner faces of said sections to 60 clamp a conductor and having at its opposite end a threaded portion, the main member having opposite sides of its intermediate portion formed with longitudinal recesses

for receiving said projections, the recesses having flat bottom faces for engaging the 65 opposite flat faces of said projections, and a nut for engaging the externally threaded projections and the threaded portion of the main member, substantially as and for the purpose described.

2. In an electrical coupling, a band member comprising two sections pivotally connected to each other at corresponding ends and provided at their opposite ends with externally threaded projections having opposing flat faces, a main member having at 70 one end engaging surfaces for co-operating with the inner faces of said sections to clamp a conductor, and having at its opposite end a threaded portion, the main member also having opposite sides of its intermediate portion formed flat for receiving the threaded projections with their flat faces engaged with the flat sides of said intermediate portion and their threaded peripheries coincident with the threaded periphery of said main member, and a nut turning on the threaded portion of the main member and onto said projections, substantially as and for the purpose specified.

3. In an electrical coupling, a band member comprising two sections, movably connected to each other at corresponding ends and provided at their opposite ends with opposing externally threaded projections 75 having flat inner faces, a main member having at one end a head having a part for co-operating with the band member to clamp a conductor and having at its opposite end a threaded portion, the main member also having the opposing sides of its intermediate portion formed with longitudinal recesses 80 for receiving the externally threaded projections, and said head being provided with shoulders extending laterally beyond said 95 projections and the shank, the recesses having flat bottoms for engaging the flat inner faces of said projections, the head and the shoulders thereof also having flat faces located in the plane of the flat bottoms of said 100 recesses for engaging the inner faces of said projections, and a nut for engaging the externally threaded projections, and threaded portion of the main member and bearing 105 against said shoulders, substantially as and for the purpose specified.

In testimony whereof, I have hereunto signed my name in the presence of two attesting witnesses, at Syracuse, in the county of Onondaga, in the State of New York, this 120 20th day of July, 1910.

CARL H. BISSELL.
